UNITED STATES PATENT OFFICE.

CARLOS BENETTI, OF BARCELONA, SPAIN.

BOTTLE CLOSURE.

Application filed May 5, 1925, Serial No. 28,249, and in Spain March 20, 1925.

The subject of the present patent application is a hygienic closure for bottles.

The closures for bottles known and used up to date are very unpractical from the 5 hygienic point of view, for they are continually coming in contact with foreign bodies, and they can therefore never be completely hygienic.

The invention which is the subject of the 10 present application overcomes this difficulty, and offers to the trade a closure which can be kept always hygienic, for all contact with foreign bodies is avoided. It is also easy to manufacture, simple in form, and durable, 15 and it should be of great use to the trade.

An embodiment of the invention is shown, by way of example, in the accompanying drawing in which:

Fig. 1 shows in section a bottle neck with 20 stopper inserted and with protecting cover.

Fig. 2 shows in side elevation the protecting cover alone.

Fig. 3 shows the stopper and the cover partly in section.

25 The outer shell or cover 1 completely covers the stopper 2 in the form of a cone, so that between the under part and the cover a free space remains which serves for the introduction of the neck of the bottle, and 30 closes it tightly.

The stopper can be made out of any appropriate substance, for example cork, rubber, etc. It must, however, be an elastic

substance, so as to allow the upper part of the stopper to be pushed into the inside of 35 the cover. It is evident from the foregoing description that the stopper, when it is introduced into the neck of the bottle, cannot come in contact with any foreign bodies.

The cover is spread over the under end of 40 the stopper, so when the stopper is taken out or put in, the inner part of the same, that is to say the part which comes in contact with the liquid or other contents of the 45 bottle, is never, under any circumstances, in danger of becoming infected, for it cannot come in contact with other objects.

The outer part, or cover, may be made 50 of porcelain, brass, nickel, aluminum, or other equally appropriate material.

Claim:

A closure for bottles comprising in combination a ball shaped cover, an annular rib in the upper portion of said cover provided by the pressing of an annular groove 55 into the outer surface of said cover, and a conical stopper of suitable elastic material and held by said annular rib at its top part which is larger than the lower part so that said stopper as well as the bottle neck are 60 protected by said cover from contact with foreign bodies.

In testimony whereof I have signed my name to this specification.

CARLOS BENETTI
